DESIGN.

—o—
A. B. CAMERON.
PANEL.

No. 20,445.

Patented Jan. 6, 1891.

20,445 and 20,446. PANEL.—*Alton B. Cameron*, Williamsport, Pa.
Application filed November 29, 1890. Serial Nos. 373,073 and
373,074. Term of patents 14 years.

UNITED STATES PATENT OFFICE.

ALLAN B. CAMERON, OF WILLIAMSPORT, PENNSYLVANIA.

DESIGN FOR A PANEL.

SPECIFICATION forming part of Design No. 20,445, dated January 6, 1891.

Application filed November 29, 1890. Serial No. 373,073. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, showing my said design and forming part hereof.

My design consists in the circular elevation A, which appears upon the surface of the panel. At the center of said elevation A appears a circular elevation B, having a concave face. Extending from and tangential to the

periphery of elevation A are grooves or channels C. The appearance of a number of triangular elevations, each having one side more inclined than the other, is thus produced on the surface of the elevation A. 15

I claim—

The design for a panel, substantially as 20 herein shown and described.

ALLAN B. CAMERON.
